UNITED STATES PATENT OFFICE.

CHARLES R. KEERAN, OF BLOOMINGTON, ILLINOIS.

VACUUM-SEAL FOR JARS.

973,512.

Specification of Letters Patent. Patented Oct. 25, 1910.

Application filed August 10, 1909. Serial No. 512,224.

To all whom it may concern:

Be it known that I, CHARLES R. KEERAN, a citizen of the United States, residing at Bloomington, in the county of McLean and 5 State of Illinois, have invented new and useful Improvements in Vacuum-Seals for Jars, of which the following is a specification.

This invention relates to a vacuum seal 10 for fruit and like jars or receptacles, the object of the invention being to provide a simple and inexpensive construction of seal which when applied will be held by external atmospheric pressure in position to hermetically seal the mouth of the jar or receptacle.

A further object of the invention is to provide a vacuum seal which may be readily punctured to admit air to the jar so that the 20 seal may be conveniently opened.

Still another object of the invention is to provide a vacuum sealing cap having novel means for effecting a hermetic connection with the jar or receptacle and a 25 novel means for closing communication between the interior of the jar and the atmosphere, which closing means may be conveniently punctured to destroy the vacuum connection when it is desired to open the jar 30 for the removal of its contents.

A still further object of the invention is to provide a means for temporarily holding the seal in position until the vacuum sealing action is effected.

35 The invention consists of the features of construction, combination and arrangement of parts hereinafter fully described and claimed, reference being had to the accompanying drawings, in which:—

40 Figure 1 is a vertical section through the upper portion of a jar showing the application of the invention with the clip or retaining device in position. Fig. 2 is a top plan view of the same.

45 Referring to the drawing, 1 designates the body of a Mason or other type of fruit jar or receptacle provided upon its neck portion with external cam ribs or threads 2.

The seal embodies a cap 3 having at its 50 outer edge a depending flange 4 to inclose the mouth of the jar above the threads or cam ribs 2. This cap, which is made of sheet metal or other suitable material, is provided with a depressed panel 5 coextensive in diameter with the mouth of the

jar and having a central depressed, circular receptacle 6 provided with a vent opening 7.

The construction described provides between the flange and marginal edge of the panel 5 an annular rim 8 forming a groove 60 9 to receive a sealing ring 10 which is adapted to rest upon the rim edge of the mouth of the receptacle and to form a hermetically tight joint between the same and the cap. This sealing ring is composed of wax and 65 some suitable fibrous material combined in proper proportions to prevent disintegration of the wax and to render the ring flexible even when the wax is cold. The receptacle 6 is adapted to receive a disk or plug 70 11 of the same composition as the sealing ring, which plug is designed to tightly fit within said receptacle and to close the opening 7.

A clip or retainer is provided to temporarily hold the parts of the seal in position while the sealing action is being effected. This comprises a bail 12 adapted to extend across and down upon the sides of the cap and neck of the jar and provided with lugs 80 13 to engage the threads or ribs 2. In the cross bar or body of the bail, adjacent the ends thereof, are formed outwardly inclined or curved slots 14 for the passage of the free ends of a bowed pressure spring 15, 85 which is arranged below said bar to bear against the inserted plug 11.

In operation, the jar is filled with boiling fruit and the cap 3 is then placed in position to close the mouth of the jar and with the sealing ring 10 disposed in the groove 9 resting upon the rim edge of the jar. The plug 11 is then inserted within the receptacle 6 to close the opening 7, after which the bail 12 is applied in position and secured down until the spring 15 engages the plug with sufficient force to hold the cap and plug in applied position. The heat of the contents of the jar will then fuse or melt the wax contained in the sealing ring and plug and firmly fasten the same in position within the groove 9 and receptacle 6, at the same time securing the cap to the rim edge of the jar and the seal within the receptacle, forming a hermetically tight closure at all points. The clip is retained in position until the contents of the jar cool and condense the air contained in the top of the jar, whereby a partial vacuum is formed in the latter, causing the cap or 100 105 110

seal to be held in connection with the jar both by the adhesion between the ring 10, cap and rim edge of the jar and the external atmospheric pressure against the cap. The 5 clip may then be removed, as a secure and permanent seal will be effected which will be proof against the accidental detachment of the cap for entrance of air into the jar. When it is desired to remove the cap in 10 order to break the seal, an opening is punched through the plug 11 in line with the opening 7 to allow air to enter the jar, whereupon the cap may be readily pried or forced off.

15 As a result of the construction described, a simple, cheap and efficient type of closure is provided which does not extend to any material extent beyond the jar and may be applied and removed with facility. The cap 20 5 may be employed any number of times, it being merely necessary to employ a new composition sealing ring and plug each time it is used for sealing purposes.

I claim:—

25 1. The combination with a jar having external threads, of a vacuum sealing disk adapted to effect a sealing connection with the jar, said disk being provided with a vent opening, and a fusible plug for closing 30 said opening, a retaining bail adapted to engage the threads and provided with short inclined transverse slots in the cross portion thereof and a bowed retaining spring adapted to bear upon the plug and having 35 its ends slidably and frictionally engaged with said slots and retained thereby to prevent movement of the spring longitudinally of the bail.

2. The combination with a jar, a vacuum

sealing disk adapted to close the mouth of 40 the jar, said disk being provided with a vent opening, and a fusible plug for closing said opening, of a bail-shaped retainer adapted to engage the jar and having outwardly and upwardly inclined short trans- 45 verse slots therein, and a bowed pressure spring extending longitudinally beneath the cross portion of the bail and having its ends slidably fitted in said slots and its convex central portion arranged to bear upon the 50 plug, said ends of the spring being held by the slots to prevent movement of the spring longitudinally of the bail.

3. A vacuum seal comprising a cap having a flange and a depressed body portion, forming a circular retaining groove between said flange and body portion, the body portion also having a central circular depressed panel of some depth provided in the bottom wall thereof with a vent opening, a sealing ring composed of a non-heat insulating fiber and wax fitted within said circular groove and co-extensive in width and in depth there-with, and a circular plug composed of a similar composition adapted to fit within 65 and close said circular panel and the vent opening therein, said plug being co-exten-sive in depth with the panel whereby its upper surface is adapted to lie flush with the upper surface of the body portion of 70 the sealing cap.

In testimony whereof I affix my signature in presence of two witnesses.

CHARLES R. KEERAN.
